WATER-BORNE FLARE AND THE LIKE

Conrad David Schermuly, Alfred James Schermuly, and Charles Schermuly, Parkgate, Newdigate, England

Application June 22, 1945, Serial No. 600,952

In Great Britain April 5, 1944

1 Claim. (Cl. 102—7)

1

This invention relates to water-borne flares and the like and has for its principal object to provide improved means for igniting the same.

In our application Serial No. 546,162, filed July 22, 1944, we have described a rocket-discharging device comprising an inner casing, a buoyancy chamber on said inner casing, an outer casing surrounding said inner casing and buoyancy chamber, a rocket in said inner casing, means for ejecting said inner casing from said outer casing, and means for ejecting said rocket from said inner casing and for igniting said rocket. The whole device is dropped from aircraft into water. The casing is separated and the rocket ignited by an arrangement of fuzes and bursters. It has been found that occasionally the rocket fails to ignite, due to the fact that during separation of the casing a partial vacuum is created which prevents ignition of the fuze for igniting the rocket. The separation of the casing takes place prior to or simultaneously with the ignition of said fuze.

According to the present invention a water-borne illuminating device comprises illuminating means such as a rocket and/or flare contained in an inner casing, a buoyancy chamber on said inner casing, an outer casing which either surrounds the inner casing in two separable parts or is separably secured to said buoyancy chamber, a delay fuze for igniting said illuminating means, and means for separating said outer casing after the ignition of said delay fuze.

One embodiment of the invention will now be described by way of example with reference to the accompanying drawing. The figure is a view partly in section of the lower end of a device of the type described in our co-pending application Ser. No. 546,162.

A rocket or flare 1 is contained within an inner casing 2 which is provided with a buoyancy chamber 3. Surrounding the lower end of the buoyancy chamber 3 is an outer casing 4, the joint 5 between the outer casing and the buoyancy chamber 3 being weak so that the outer casing 4 may readily be separated from the buoyancy chamber 3. The outer casing 4 is provided at its lower end with a weighted cap 6 which ensures that the whole device maintains the correct position when dropped into water. A metal ring 7 is secured to the lower end of the inner casing 2 and a plate 8 is screwed into said ring 7. Screwed into the plate 8 is a bobbin 9. A delay fuze 10 is wound round the bobbin 9 with one end of the fuze 10 embedded in a charge 11 of powder carried in a recess in the top face of the bobbin 9 and the other end of the fuze 10 embedded in

2

a charge 12 of powder contained in a recess in the plate 8. Below the plate 8 is another plate 13 and between these two plates are located cardboard spacers 22 and a disc 14 of primed cambric from which a short length of quickmatch 15 leads to the charge 12. The plate 13 has a central hole 16, an eccentrically placed hole 17 and an annular recess 18 in its lower face. The recess 18 is filled with a separating charge 19 and a length of quickmatch 20, which passes through the hole 17, connects the disc 14 and the charge 19. Secured in the cap 6 and projecting through the hole 16 is a contact fuze 21 adapted to be operated when the device strikes the water.

15 When the device is dropped from an aircraft and strikes the water, the contact fuze 21 is actuated and the flash therefrom ignites the disc 14 which, through the quickmatch 15, ignites the charge 12 which in turn ignites the delay fuze 10. 20 The disc 14 also ignites the quickmatch 20 which fires the separating charge 19 by means of which the outer casing 4 becomes separated at the weak joint 5 from the buoyancy chamber 3 on the inner casing 2, the latter then rising to the surface of 25 the water. After the delay fuze 10 has burned through, it ignites the charge 11 the flash from which ignites the rocket or flare 1. It will be seen that the delay fuze 10 is ignited before the firing of the separating charge 19 by which the 30 outer casing 4 is separated.

The discharge of the rocket or flare 1 from the inner casing 2 may be effected in any convenient manner, as for example in the manner described in the said application Serial No. 546,162.

35 When it is desired that the flare 1 should not leave the casing 2, but should burn while floating on the water, the charge 11 may be dispensed with and the delay fuze 10 led to the top of the flare 1.

40 We claim:

A water-borne illuminating device comprising an inner casing, illuminating means contained in said inner casing, two plates located in the lower end of said inner casing below said illuminating means, a recess in the upper of said plates, a charge of powder in said recess, a delay fuze one end of which is embedded in said charge, a primed cambric disc between said two plates, an annular recess in the lower face of the lower of said plates, 45 a separating charge of powder in said annular recess, a piece of quickmatch connecting said cambric disc with said charge, a second piece of quickmatch connecting said cambric disc with said separating charge, a buoyancy chamber secured 50 to said inner casing, an outer casing enclosing 55 to said inner casing,

the lower end of said inner casing and secured to said buoyancy chamber by a weak joint, a contact fuze in the lower end of said outer casing adapted upon actuation to ignite said cambric disc which on the one hand ignites said first piece of quickmatch, said charge of powder and said delay fuze and on the other hand ignites said second piece of quickmatch and said separating charge, whereby said outer casing is separated from said buoyancy chamber after said delay fuze has been 10 ignited.
